UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LIGHT-PROJECTING DEVICE.

Original application filed March 18, 1925, Serial No. 16,552. Divided and this application filed December 3, 1925. Serial No. 73,010.

My invention relates to a light projecting device. More in particular, it relates to a device which is especially adapted for use as a traffic signal.

5 Among the objects of my invention are to provide an improved projector in which a hood and a lens are used and which may be removed as a unit, and to provide a construction in which the hood, the lens, the 10 reflector and the light source may be removed as a unit from the projector.

To accomplish the foregoing my invention comprises means hereinafter more fully set forth and claimed, reference being had to 15 the accompanying drawings in which Fig. 1 shows a pendant type of traffic signal in elevation; Fig. 2 shows a second form of the traffic signal in perspective with the hood element removed; Fig. 3 shows one of the 20 hood elements in perspective; Fig. 4 shows in perspective one of the projector elements comprising the hood element and the reflector element assembled; Fig. 5 is a section through the projector element of Fig. 25 4; Fig. 6 shows a section of the form of housing, a number of which are shown assembled in Fig. 1; Fig. 7 shows a standard in section which is adapted to serve as a support for the form of signal shown in Fig. 1 30 when it is desired to place the signal upon an upright. Fig. 8 is a drawing on a larger scale than the drawing of Fig. 5 of the reflector element of the projector showing the path of the rays. This drawing is shown 35 in section and also shows the focal points of the different forms of surfaces which go to make up the reflector.

Referring more in detail to the drawings, it will be seen that the reflector, Fig. 8, is 40 provided with a rear opening 2 through which a socket for a light bulb may be inserted. The reflector is also provided with a front opening 3 through which the rays that go to make up the beam from the projector pass forward. The rear portion 4 of the reflector immediately around the opening 2 and extending for some distance therefrom is paraboloidal in form. Beyond the 45 paraboloidal region and extending as far as the ridge 5 the section 6 is spherical. The portion of the reflector 7 to the right of the ridge 5 is also spherical but has a different

curvature than the region 6. Beyond the spherical region 7 the flaring portion 8 of the reflector is paraboloidal or it may be 55 a surface of revolution generated by any one of the conics.

The center of curvature of the spherical region 6 I have indicated at the point 9. The point 10, on the other hand, is the focal 60 point for the paraboloidal regions 4 and 8 and the central point of the spherical region 7. The reflector, therefore, as shown in the drawing consists of a surface of revolution formed by revolving a curve about the axis 65 of the reflector, which axis passes through the focal point 10. The curve as shown consists of four conics 4, 6, 7 and 8, three of which, namely, curves 4, 6 and 8, are so positioned with respect to the focal point that 70 rays originating in the focal point are reflected to the right of the focal plane, while the fourth curve, namely, curve 7, is so positioned with respect to the focal point that the rays originating in the focal point are 75 reflected to the left of the focal plane. It will be seen, therefore, that these conics are all focalizing curves with their concave sides facing toward the focal point, but curves 4, 6 and 8 are facing toward the left of the 80 focal plane, while curve 7 is facing toward the right of the focal plane. The arrows in Fig. 8 indicate how the rays that go to make up a beam from a light source located at the point 10 pass out of the reflector. It will be 85 seen that with a reflector of this type a very wide angle of projection is obtained.

The casing for the reflector is shown in detail in Figs. 4 and 5. The front element of the casing is provided with a flange 11 and 90 with a depression in the form of a forwardly sloping zone 12, (Fig. 5), from the forward end of which zone the collar 13 extends. The reflector is mounted with the outer spherical section 7 resting against zone 12 of 95 the front element. The reflector is clamped in position by means of a number of spring strips 14, the forward ends of which are secured to the front plate by means of screws 15. A rear plate 16 serves as a rear support 10 for the reflector and is fastened to the springs 14 by means of screws 17. This rear support is provided with a rearwardly projecting collar 18 through which the socket 19 which sup-

ports the light source 20 projects. The center of this light source, it will be understood, is placed to coincide with the focal point 10, Fig. 8, of the reflector. It will be seen that 5 the front plate is provided with a series of screw holes in order that the projector element may be properly secured to the casing of the unit, as for example, by means of screws 11^a, Fig. 2.

- 10 The visor 21 of the projector is made with an annular portion 21^a which serves to hold the lens 22. This lens is locked in position between a felt or rubber cushion on one side and the ring-like spring 23. It will be seen that 15 to the rear of the annular portion 21^a there is provided a flange 24 which is split on the underside, Figs. 3 and 5, and by means of a screw or bolt 25 this flange may be tightly clamped to the collar 13 of the front plate. 20 With this construction if it is desired to remove the electric lamp from within the reflector it is only necessary to loosen the bolt 25 and remove the hood element from the collar 13. The hand may then be inserted 25 through the front opening 3 of the reflector to reach the lamp.

In case it is desired to reach the socket 19 the projector unit may be removed as a whole by removing the screws 11^a. It will be understood that the cord 26 inside the housing may be made of any suitable length in order that the projector element may be withdrawn without difficulty. All of the cables 26 within the unit may be connected 35 to a common terminal element to which the leads from the source of power may be connected.

The type of casing shown in Fig. 1 is formed of one or more sections such as the 40 section shown in Fig. 6. These sections may be placed one on top of another and bolted together each section to the next adjoining section for example. For this purpose the lugs 27, Fig. 6, are provided with suitable 45 holes 28 through which the bolts or screws pass. In a similar manner the bottom terminal piece 29 is secured to the lowermost section of the casing.

When the casing is to be mounted on top 50 of a standard such as that shown in Fig. 7 the bottom piece 29 of Fig. 1 is omitted and the casing is set on top of the upright, Fig. 7, and screwed thereto. For this purpose the lugs 30 with the proper holes for screws or 55 bolts are provided.

The unit in Fig. 1 is provided with a cap piece 31 which is bolted to the topmost section of the casing in a similar manner. This element 31 is provided with an opening on top 60 which is closed by the cap piece 32 which latter is suitably screwed or bolted to the section 31. The cross piece 33 is in turn secured to the piece 32 and serves as a support for the whole unit. Suitable openings are 65 provided through this piece 33 through which

the cables or conductors pass into the interior of the unit, the members 32 and 31 being, of course, provided with a central opening.

In this traffic signal the visor 21 extends forward a distance equal to about twice the 70 diameter of the lens 22. Furthermore, the visor is curved shovel-shaped and with the edges sloping down to a point in proximity of the horizontal diameter of the annular section 21^a. The object in this construction 75 is to prevent exterior sources of light, such as the sun or moon or street lighting units, from striking the lens 22 and making it appear that the signal is in operation. Heretofore, such exterior sources of light have 80 produced this effect and caused error and confusion in consequence.

While in Fig. 2 the housing has been shown as one continuous section this housing may be constructed with a number of elements, 85 such as shown in Fig. 6, turned at right angles to the position shown in Fig. 6. With such an arrangement, however, some of the openings 34 through which the projector of Fig. 4 is inserted in place may be omitted, for 90 example, the openings which would otherwise appear on the underside of the casing in the form of Fig. 2. Although the casing in Fig. 6 is shown with a straight edge, the construction may be changed to be square 95 to conform with the form indicated in Fig. 2.

It will be understood that whereas I have described my invention in connection with specific construction illustrated I do not wish to be limited to such specific construction inasmuch as various modifications may be made within the scope of my invention and of the 100 claims herein contained.

What I claim as new and desire to secure by Letters Patent of the United States, is:— 105

1. In a light projector, a casing, an opening in said casing, said casing being provided with a protuberance to one side thereof surrounding said opening, a visor over said opening, means clamping said visor to said protuberance, a lens over the end of said protuberance, means retaining said lens in place, a substantially globular hollow element in said casing, means holding said element mounted with its axis parallel to the axis 110 of the protuberance and with a portion of one hemisphere of the element seated in said protuberance, the other hemisphere of said element being substantially a beam-forming reflector. 115

2. In a light projector, a casing, an opening in said casing, said casing being provided with a protuberance extending to one side of the casing, the base of the protuberance surrounding said opening, said protuberance being concave and having a cylindrical collar, a visor over said opening, means clamping said visor to the cylindrical portion of said protuberance, said visor having a cylindrical band concentric with and adjacent to the 120 125 130

cylindrical portion of said protuberance, of the protuberance and with a portion of the means in said cylindrical band for retaining other hemisphere thereof seated in said protuberance. 10
said lens in place, a hollow globular member within said casing, one hemisphere thereof being a beam-forming reflector, means holding said member mounted in said casing with the axis of the member parallel to the axis

In witness whereof, I have hereunto set my hand this first day of December, 1925.

CROMWELL A. B. HALVORSON, Jr.
